ROTARY SNOWPLOW

Egon G. Berg and Arend Voorderman, Cedar Rapids, Iowa, assignors to Universal Engineering Corporation, Cedar Rapids, Iowa, a corporation of Iowa

Application February 28, 1945, Serial No. 580,164

3 Claims. (Cl. 37—43)

1

This invention relates generally to road machinery and is particularly concerned with snow removal apparatus.

The object and general nature of this invention lies in the provision of new and improved snow removal equipment particularly adapted for highway use, especially in conjunction with snow plows of the blade type. A more specific feature of this invention is the provision of a snow removal device adapted to be mounted on a truck and used to widen the passage produced by the initial use of blade trucks. Particularly, it is a feature of this invention to provide a device for removing snow from the side walls of windrowed or piled snow banks, so constructed and arranged that only one handling of the snow is necessary.

A further and important feature of this invention is the provision of a snow removing unit that is especially adapted to be used in conjunction with both light and heavy blade type snow removal plows but which does not require additional trucks.

At the present time, snow removal practices in most general use include the initial use of light blade push plows mounted on light trucks of the type needed for various jobs throughout the year, and of which most State highway departments usually have quite a large number. These light trucks are fitted with straight blade plows and are started in operation as soon as snow begins to accumulate on the highways and ordinarily can be depended upon to sweep the snow off the highway as fast as it falls.

If the intensity of the storm increases to the point that the light trucks are unable to keep the highways clear, then the heavier trucks are brought out, equipped with heavier straight blade or V-type plows. The heavier equipment is usually able to handle moderate amounts of snowfall but, like the light weight trucks and straight blades, all that the heavier equipment can do is to push the snow to one side of the pavement, usually over onto the shoulder. With the heavier snowfalls, even the larger equipment has to be used several times at any one place, that is, it has to make several passes before a passage of sufficient width can be maintained, and at each pass all the snow previously handled on the last pass must be rehandled.

Under conditions requiring the heavier equipment, as above, the light plows are of no further use and are placed out of service while the heavy plows attempt to do all the work.

By merely pushing the snow to the sides of the road even the heavier plows are unable to get the

2

snow completely off of and away from the highway. The heavier the snowfall the larger the piles or windrows of snow along the sides, and these piles or windrows serve as obstructions which accumulate more and more snow on the exact spots where it is the most difficult to remove.

With the above factors in mind, the present invention contemplates the provision of means 10 that can be mounted on the light or heavy trucks as desired and used to remove snow from the sides of high banks and windrows piled along the sides of the highway by the blade trucks, and this without requiring any rehandling of the snow. In this 15 way, by mounting the side removal units on the light trucks very little additional equipment is necessary, yet very heavy snows can be handled easily, especially in conjunction with the initial use of the light blade trucks, followed by the 20 heavier plows and then with the light trucks equipped with the side removal units of the present invention.

Another very important object and feature of this invention is that the snow removing means 25 is so constructed as to be mounted for side operation but even though side mounted it conforms to conditions of available clearances for travel.

Front mounted plows have a basic weakness in 30 that only one cut can be taken. It is all or nothing. If the plow cannot take all of the cut it will get stuck. We therefore, as a part of our invention, provide a side mounted snow removal 35 device, but although the plow or snow removal device is side mounted, means are provided whereby the snow removal device may be swung in to the normal truck width for transportation and this is another object of our invention.

Still another important object of our invention 40 is to provide means for taking snow out in one or several horizontal cuts or layers.

These and other objects of this invention will be apparent from the following detailed description taken in conjunction with the accompanying 45 drawings, in which:

Figure 1 is a perspective of a highway truck on which has been mounted a snow removal unit constructed according to the principles of the present invention.

Figure 2 is a rear view, showing the snow removal unit swung around into a transport position.

Figure 3 is a side view of the outfit shown in Figure 2.

Figure 4 is a top or plan view, showing the snow

removal unit in the position it occupies when operating, corresponding to the position shown in Figure 1.

Figure 5 is an enlarged sectional view, taken generally along the line of 5-5 of Figure 4.

Figure 6 is a side view of the snow removal unit, corresponding to a view taken generally along the line 6-6 of Figure 5.

Figure 7 is an end view of the lower rotor, and

Figures 8 and 9 are detail views of the upper spinners.

Referring first to Figure 1, the snow removal unit with which the present invention is more directly concerned is indicated by the reference number 1 and is shown as mounted on a truck 2 of the type commonly owned and/or operated by state highway departments and the like. The truck 2 has front steering wheels 3 and rear dual driving wheels 4. The chassis 5 of the truck 2 includes frame channels 6 forming a part of the frame 7 of the truck 2. The operator's cab of the truck is shown at 8.

Rearwardly of the cab 8 the truck frame carries a turntable 15 which includes a stationary frame or base 16 mounted directly on the frame channels 6 and a rotatable turntable frame 17, connected together by suitable vertical bearing means 19 (Figure 4). Preferably, the base 16 carries a circular track 21 suitably secured thereto, and the rotatable frame has rollers or other suitable means (not shown) cooperating therewith. A pair of hydraulic units 23 and 24 are anchored at their outer ends to the base and are connected at 25 and 26 to a pivot lever 27 that is fastened to the rotatable turntable frame 17, whereby the latter may be swung about the pivot axis 19 by power. The rams 23 and 24 are operated by hydraulic power and controlled by suitable valve means in the operator's cab 8 or any other suitable location on the truck. The frame 17 has a lateral extension 28 made up of a pair of laterally extending frame members 29 and 30 to which other frame members 33, 34 and 35 forming a part of the rotatable turntable 17 are connected. The lateral frame extension 28 is reenforced by one or more cross bars 37 (Figure 2).

An A-frame 40 is erected on the turntable frame extension 28 and at its apex it has a pair of brackets 41 which are apertured to receive a shaft 43 to which a pair of links 44 and 45 are rigidly connected, as by welding. For additional rigidity gusset plates 46 may be welded to the shaft 43 and the links 44 and 45. A pair of lower links 47 and 48 are pivoted, as at 51, to a pair of brackets 52 and 53 secured to the channel 30 adjacent the outer end thereof. Preferably, a shaft or the like forms the pivots 51, and the shaft 51 has an arm 55 secured thereto and extended upwardly, as at 56, to form a stop. A hydraulic jack or ram 57 is anchored to a bracket 58 that is fixed to one of the cross bars 37, and at its other end the ram unit 57 is pivoted to the lower end of the arm 55. Extension or retraction of the ram 57 acts through the shaft 51 to raise and lower the links 44, 45, 47 and 48.

The units that cut and remove the snow comprise rotatable members, which will be referred to later in detail, mounted in a compartment 50, which includes a pair of side walls 51, and 52, and a back wall 53. A lower wall 54, of the compartment slopes forwardly and downwardly and carries lower stationary cutting element 56. Joined to the back wall 53, is a rear compartment 61, which communicates at its lower end with the

lower part of the forward chamber 50, the communication being established through an opening 63. At the upper or discharge end of the rear chamber 61, there is a plurality of flexible guide vanes 65, best shown in Figure 5. These flexible elements are rigidly fixed at their lower ends to the walls of the rear chamber 61, and at their upper ends are connected together by links 67.

The rear wall 71, of the rear chamber 61, flares outwardly at its upper end to form a backing for the flexible vanes 65, in either of their extreme positions. An operating link 73 is pivotally connected at 74, to the upper end of the adjacent deflector vane 65, and at its other end, the link 73 is pivoted at 75, to the upper end of an operating arm 76. The lower end of the arm 76 is fixed to a cross shaft 78 in bearings or the like 79.

The bearings 79 are supported on one of the two side channels 81, which are connected in any suitable way with the upper ends of the compartments 50, and 61, as best shown in Figure 1. The rear ends of these channels are apertured to receive pivots 82, by which the outer ends of the associated upper links 44, and 45, Figure 2, are connected to the compartments 50 and 61. Centrally adjacent their lower ends, the compartments 50 and 51 carry bearing plates 84, and these plates carry pivots to which the outer ends of the lower links 47 and 48 are connected. Thus, extension or retraction of the ram 57 serves to raise and lower the compartments 50 and 61 together with the rotatable elements carried therein. The deflector control shaft 78 is operated by a hand wheel 90, to shift the deflector vanes 65 into the desired position.

The uppermost rotary element is indicated by the reference numeral 100, and comprises a spinner which includes a shaft 101 having a plurality of discs 102 mounted thereon. As best shown in Figure 9, the peripheral portion of each disc 102 carries a plurality of knives 104. As best shown in Figure 5, the shaft 101 is supported for rotation in bearings 105 and 106 mounted on the side walls of the forward compartment 50. A lower spinner 108, similar in construction to the one just described, is mounted in bearings 109. The lower spinner 108, includes a shaft 111, discs 112, and knives or cutting elements 113, fixed to the peripheral portions of the discs 112, as best shown in Figure 8. As best shown in Figures 3 and 5, the upper discs 102 are mounted on their shaft 101 in staggered relation with respect to the discs 112 of the lower spinner 108.

A combination rotor and impeller 116 is mounted on a shaft 117 in the lower portion of the front chamber 50. The rotor and impeller member 116 is of particular construction. As best shown in Figure 5, the rotor 116, includes a pair of heads 121 notched peripherally as at 122 to form a series of generally radially extending arms 123. Each pair of arms receives a pair of cross members 125 and 126 fixed as by welding to the outer end of the arms 123. The outer members 126 are sharpened, as at 127, to form cutting blades spaced radially from the inner cross members 125. V-shaped sheets 131 are disposed in the notches 122 and are welded at their ends to the edges of the arms 123. One or more struts 132 connect the intermediate portions of the cross members 125 with the corresponding portions of the blades 126 for strengthening and reenforcing the latter. As best shown in Figure 6, the rotor 116 is mounted so that the rear portion thereof moves through the

throat 63, and upwardly in the lower portion of the rear chamber 61, the rear wall of the rear chamber 61 being curved, as at 134, to correspond to the path of movement of the rotor blades 126.

Referring now to Figures 5 and 6; a sprocket 141 is mounted on the inner end of the shaft 101 and a similar sprocket 142 is mounted on the inner end of the shaft 111. A roller chain 144 is trained over these sprockets as shown in Figure 6, so that the shafts and associated spinners are rotated in opposite directions at its lower end. The chain 144 is trained over a sprocket 146 fixed to the inner end of the rotor shaft 117. As best shown in Figure 3, shield sheets 148 and 149 are carried in the forward compartment 50 to enclose the chain 144 and associated parts.

Power for driving the elements described above is provided for in the form of a motor 160 mounted on the turn table frame 17 adjacent the A-frame 40. Suitable power transmission mechanism, including controlling clutches and the like, are enclosed by a casing 161, and serves to drive a transverse drive shaft 162 (Figure 4). One or more sprockets 163 are fixed to the outer end of the drive shaft 162, and receive chain means 164 which transmits the drive from the drive shaft 162 to sprockets 165 fixed to the rotor shaft 117, axially inwardly of the sprocket 146.

The operation of the structure described above is substantially as follows:

Figure 3, shows the turntable 17 swung around into a transport position in which the compartment containing the spinners and rotor is disposed in a position generally behind the truck cab 8. As best shown in Figure 2, in this position of the turntable 17, the motor 160 is disposed at one side of the truck substantially over the left rear wheels while the rotor and associated parts are disposed generally over the right rear wheels of the truck. When the turntable has been swung into the position just described, a truck equipped with my snow removal unit is not substantially wider than any ordinary truck. The turntable is swung into and out of transport position by operation of the hydraulic rams 23 and 24.

When it is desired to bring my snow removal units into operation all that the operator has to do is to actuate the proper valve to cause the rams 23 and 24 to swing the turntable 17 around into the position shown in Figures 1 and 4. This disposes the front compartment 50 with its open side facing forwardly. The truck 2 is then driven along side the snow bank or piled or windrowed snow, and the ram 57 is then actuated to lower or raise the chamber 50 as conditions may require. The spinners and rotor are then driven while the truck is driven forwardly. The spinners, together with the blades 126, break up the snow into small pieces and as the outfit progresses forwardly the snow thus removed is impelled through the throat 63 by the rotor 116 and directed upwardly through the rear chamber 61.

The deflectors 65, are adjusted into the proper position to throw the snow entirely away from the zone of operation. As will be seen from Figure 1, the snow removal unit overhangs the truck at one side thereof so that the unit may be advanced into a snow bank situated, for example, along the shoulder of the highway while all wheels of the truck remain on the pavement. This affords adequate traction. Usually, even a high bank

of snow will seldom require more than two passes, the first to remove the upper half of the snow, and the other to remove the lower half, to thus remove all of the snow at the side of the highway for a width equal to the width of the unit 50. The deflectors throw the snow entirely away from the zone of operation so that, if it should be desired to clear off the shoulders, only one or two additional passes will be required since there is no rehandling of the snow.

By means of our invention, snow can be removed in one or more horizontal cuts or layers, as desired. For instance, a shallow cut may be made to remove a heavy ice crust and then heavier, deeper cuts to remove unpacked snow. Benches or ledges of snow may be constructed to prevent vehicles from leaving the road. Horizontal cuts may be made over guard rails, rocks or other obstacles to permit later accumulations of snow to be piled up.

It is to be understood that our invention, as defined by the appended claims, may be incorporated in structures differing from that described above.

25 We claim as our invention:

1. In a snow removal device, a mobile support, a turntable mounted thereon for rotation about a vertical axis, a frame mounted on the turntable, the said frame having a portion thereof, generally to the rear of the vertical axis, extending transversely beyond one side of the mobile support, a braced framework mounted upon and extending upwardly from the transversely extending portion of the frame, a casing disposed forward of the frame extension and at the side of the mobile support, vertically swingable arms extending generally forwardly from the braced framework and operatively connecting the said braced framework and the casing whereby movement of the casing is permitted in a vertical plane substantially parallel with the direction of motion of the mobile support, and means for securing the arms and the casing in any desired position.

2. In a snow removal device, a mobile support, a turntable mounted thereon for rotation about a vertical axis, a frame mounted on the turntable, the said frame having a portion thereof, generally to the rear of the vertical axis, extending transversely beyond one side of the mobile support, a braced framework mounted upon and extending upwardly from the transversely extending portion of the frame, a casing disposed forward of the frame extension, generally forward of the vertical axis and at the side of the mobile support, vertically swingable arms extending generally forwardly from the braced framework and operatively connecting the said braced framework and the casing whereby movement of the casing is permitted in a vertical plane substantially parallel with the direction of the motion of the mobile support, and means for securing the arms and the casing in any desired position.

3. In a snow removal device, a mobile support, a turntable mounted thereon for rotation about a vertical axis, a frame mounted on the turntable, the said frame having a portion thereof, generally to the rear of the vertical axis, extending transversely beyond one side of the mobile support, an A frame mounted upon and extending upwardly from the transversely extending portion of the frame, a casing disposed forward of the frame extension and at the side of the mobile support, an upper pair of spaced parallel arms hingedly connected between the casing and the A frame at 70 the upper part thereof, a lower pair of spaced

parallel arms hingedly connected between the frame extension and the casing, the said upper and lower pairs of arms being parallel, and of substantially equal lengths, and lifting means operatively connected with the lower arms and adapted to selectively lower or raise the said arms and the casing.
